RESILIENTLY SUPPORTED TILTING CHAIR

Philip Mednick, Brooklyn, N. Y.

Application January 6, 1947, Serial No. 720,418

2 Claims. (Cl. 155—77)

1

This invention relates to new and useful improvements in "easy chairs," and more especially to the reclining type of chairs, and it has for its purpose to provide a chair which is comparatively simple of construction, infallible in operation and non-costly to manufacture, as it consists of but a few parts.

While the chair is mainly constructed as a reclining chair, it may also be used as an ordinary chair.

With the above and other objects in view, this invention consists of the novel features of construction, combination and arrangement of parts, hereinafter fully described, claimed and illustrated in the accompanying drawings forming part of this application, and in which similar characters of reference indicate corresponding parts in all views, and in which:

Figure 1 is a top plan view of a chair constructed according to my invention.

Figure 2 is a side elevational view of same.

Referring more particularly to the drawings, the numerals 10 and 11 indicate the frame members of a chair, said members being formed with eyelets 12, 12 adapted to receive a shaft 13, which latter holds the opposite frame members together. A seat 14 is secured to bracket members 15 which on their downwardly projecting parts have lugs 16 at the top thereof, and lugs 18 at the bottom. Springs 19 and 34 are interposed, 19 between the lugs 18 of the brackets 15 and the frame members 10 and 11; and 34 between the lugs 16 and said frame members.

Said springs are for the purpose of imparting springiness to the chair, when the latter is in a reclined position.

Rods 20 are mounted beneath the seat and within the said frame structure; said rods are adapted to slide through openings 22 formed in lugs 23; these lugs are integral with the bracket members 15, 15, and arranged one upon each thereof and underneath the latter; said rods further slide through openings 21 formed in lugs 35 integral with the frame member 11. The rods 20 are provided with springs 24 and have at one end collars 25.

Arms 26 are fast on the shaft 13, which latter in turn is fixedly secured to the frame member 10, as at 27, while short strong chains 28 connect one end of said rods to the arms 26.

The chair structure is provided with the usual upholstered parts 29 and 30.

The operation of my invention is as follows: when it is desired to use the chair as a reclining chair, the person sitting in the chair leans back against the rear portion 30, whereupon the frame 10 will tip back somewhat, as the movable arm

26 fixedly connected to the shaft 13 moves backward and simultaneously also pulls the rods 20 rearwardly until they are arrested by the stop collars 25 striking against the lugs 23.

5 The shaft 13 is also fixedly connected to the frame member 10, so that in connection with the backward movement of the arm 26, the latter will move rearwardly together with said frame member 10, and thus permit a reclining position 10 of the chair.

15 It is obvious that changes may be made in the form, construction and arrangement of the several parts, as shown, within the scope of the appended claims, without departing from the spirit of the invention, and I do not, therefore, wish to limit myself to the exact construction shown and described herein.

What I claim as new, and desire to secure by Letters Patent of the United States, is:

20 1. In an easy chair of the reclining type, two partially rectangular spaced front frame members, a shaft turnably connected to the latter, two spaced rear frame members fixedly secured to said shaft, and two arms fixedly mounted upon 25 the latter, brackets arranged between the front frame members, a seat supported by said brackets, portions downwardly projecting from said brackets, lugs arranged at the top and bottom of said projecting portions, and springs mounted between each of said lugs and the respective front and rear frame members, lugs formed with openings therein and being integral with said brackets, and other lugs having openings therein and being integral with the front frame members, rods sliding in the openings in the lugs of the brackets and the openings in the lugs in the front frame members, chains securing said rods to the arms, and springs mounted on said rods between the lugs on the brackets and the lugs on said frame members.

35 2. In an invention, as claimed in claim 1, and wherein stop collars are mounted upon the ends of said rods, whereby to arrest the outward movement of the latter at a predetermined stage.
